UNITED STATES PATENT OFFICE.

ALBERT B. PEDERSEN, OF EUREKA, UTAH.

AIR COMPRESSOR.

Application filed October 23, 1922. Serial No. 596,329.

To all whom it may concern:

Be it known that I, ALBERT B. PEDERSEN, a citizen of the United States, and a resident of Eureka, in the county of Juab and State of Utah, have invented certain new and useful Improvements in Air Compressors, of which the following is a specification.

This invention relates to improvements in air compressors.

The present invention more particularly relates to improvements over my Patent No. 1,333,774, issued March 16, 1920. In the patent referred to an air compressor is disclosed especially adapted for inflating tires of motor vehicles or the like wherein the air compressed is submitted to two stages of compression, one of said stages occurring continuously, while the other is controlled by the pressure within the vehicle tire being inflated or other receiver for the compressed air.

The object of the present invention is generally to improve the construction and operative efficiency of the pump or air compressor disclosed in my previous patent.

The present invention is illustrated by way of example in the accompanying drawings, in which:—

Figure 1 is a view in side elevation of the air compressor or pump when fully assembled, and

Figure 2 is a vertical sectional view of the same taken in a plane at right angles to Figure 1.

Referring to the drawings more particularly, the device may comprise the two cylinders C and C', the two pistons P and P' operable respectively within said cylinders and a crank shaft K carrying upon each end a fly wheel F, said crank shaft being connected to the pistons P and P' for operating the same.

More specifically the cylinder C may consist in a hollow cylindrical casting having formed upon its outer surface the annular rims or cooling fins 10. The cylinder may have its one end closed by a base plate 11. The base plate 11 may have threaded into its one end a nipple 12, said nipple extending below the base plate 11 and being formed with the laterally extending inlet passages 13. The one end of the nipple 12 is bevelled upon its interior periphery and

adapted to seat a valve member 14. The valve member 14 has a stem 15 extending therefrom and said stem being operated upon by a spring 16 for yieldingly holding the valve member 14 in its seated position. The cylinder C may have formed therewith a pair of supporting members 17, said members extending upwardly from the cylinder and each member terminating at its upper end in a semi-circular and laterally extending shaft bearing portion 18 by which the end portions of the crank shaft K may be journaled.

The cylinder C' may also be provided with cooling fins 19 and its upper end being closed as at 20 and having threaded in this end a valve cage 21 which is in the form of a sleeve within which there is positioned a valve member 22, the inner end of the member 21 being bevelled and adapted to seat the valve member 22. The valve member 22 is formed with a stem 23 which is pressed inwardly by a spring 24. A nipple 25 is threaded into the outer end of the member 21 and adapted to hold the spring 24 in position. Also a sleeve 26 may be positioned upon the stem 23 to serve as a guide therefor and adapted to slide within the coil spring 24. The nipple 25 may be threaded interiorly as at 27 whereby a hose connection or the like may be made therewith. The cylinder C' also is formed with a pair of depending members 28, each of which terminates in a bearing cap 29 adapted to fit upon the bearing portions 18 of the cylinder C. The caps 29 may be secured to the bearing members or portions 18 by suitable flange bolts 30. The extensions 17 of the cylinder C and also the extensions 28 of the cylinder C' may be formed with suitable reinforcing ribs as at 30.

As seen in the drawings the cylinder C is of greater diameter than the cylinder C'. The piston P fits within the cylinder C and the piston P' within the cylinder C' and these pistons are integrally connected by a body portion D, said body portion consisting in a semi-circular portion 31, the ends of which terminate in a substantially inverted V-shaped portion 32. The body member is hollow to provide a passageway 33 which extends entirely thereabout and is adapted to establish communication between the interior of the pistons P and P'

as illustrated in Figure 2. The pistons P and P' are likewise hollow and each formed at its outer end with a head closure 34. In the head 34 of the piston P there is threaded therethrough a nipple 35 which has its lower end formed with an inwardly extending rib or flange 36 which is bevelled and adapted to seat the valve member 37. The valve 37 is provided with a stem 38 which passes through a spider guide 39 and is yieldingly held against upward movement by the coil spring 40. In head 34 of the cylinder P' is also a nipple 41 threaded therethrough and having its outer end bevelled to seat the valve member 42, said valve member being likewise spring controlled by the means of a compression spring 43 and adapted to be yieldingly held against outward movement by said spring. The pistons P and P' are each provided with suitable packing rings as at 44.

The body member D has a portion of its sides closed as at 45, said portions occurring adjacent the upper end of the body member 25 and being adapted to support a wrist pin 46, said wrist pin 46 in turn journaling the upper end of a connecting rod 47, said connecting rod being properly journaled upon the crank portion of the crank shaft K at its 30 other end as illustrated in Figure 2 of the drawings.

In the operation of the present device, a crank shaft K may be driven through any suitable power means. Preferably a power belt should be passed over one of the fly wheels F and in this way rotative movement transmitted to the crank shaft K. Upon upward movement of the pistons P and P' a suction will occur whereby to lift 35 the valve member 14 and draw air within the cylinder C. Upon downward movement of the pistons this air will be compressed and caused to pass into the interior of the piston P' and from thence into the interior 40 of the piston P' then lifting the valve 42 and escaping into cylinder C'. As the pistons P and P' continue to move upward if no greater resistance is offered to the lifting 45 of the valve 22 than that given by the compression spring associated with this valve, said valve will immediately lift and permit the air to escape to the tire being inflated.

It is of course to be understood that the air will receive a certain degree of compression, while within the pistons P and P' this 50 is entirely obvious from the structure and operation of the device. Upon the tire becoming inflated and causing a power pressure upon the valve member 22 then the air will receive a second compression, while within the cylinder C' this compression will be sufficient to overcome the pressure of the air within the tire casing plug the resistance of the spring 24 associated with the valve 55 member 22. As is obvious by inflating a tire

with a pump of this character a uniform rise in the pressure of air within the tire casing may be had.

While I have shown and described the preferred form of my invention, I wish it to be understood that I am aware of the fact, that the construction, combination and arrangement of parts may be changed by those skilled in the art without departing from the spirit of the invention, as indicated by the appended claims.

I claim:

1. In a device of the character described, a cylinder disposed vertically with relation to its bore, arms extending from said cylinder terminating in bearing members, a crank shaft supported by said bearing members, a second cylinder having arms extending from the one end thereof, each arm terminating in a bearing cap and adapted to seat upon the bearing members of the first named cylinder whereby to support the second cylinder in axial alignment with the first named cylinder, a crank shaft supported by said bearings, a piston within each cylinder, and connecting means between said crank shaft and pistons whereby the pistons may be reciprocated with the rotation of said crank shaft, and hollow connecting means between the pistons whereby the pistons are placed in communication with each other. 95

2. In a device of the character described, a base plate having an upstanding cylinder formed thereon, said cylinder having its free end terminating in a pair of supporting arms and each arm terminating in a laterally extending bearing member, a crank shaft journaled by said bearing member, a second cylinder having a pair of arms each terminating in a bearing cap extending from one end thereof, and said caps being adapted to be positioned upon the bearings of the first named cylinder whereby to support the second cylinder in axial alignment with the first cylinder, a piston within each cylinder, and connecting means between said crank shaft and pistons whereby the pistons may be reciprocated with the rotation of said crank shaft, and hollow connecting means between the pistons whereby the pistons are placed in communication with each other. 100

3. In a device of the character described, a pair of aligned cylinders, a hollow piston in each cylinder, integral means for connecting said pistons comprising a hollow casting consisting in a semi-circular portion and V-shaped portion adapted to establish communication between the interior of said pistons and also adapted to have a crank shaft extending therethrough and turnable therein, and means for connecting the crank shaft to the casting whereby to cause reciprocation of the pistons with the rotation of said crank shaft. 115

4. In a device of the character described, 120

a pair of aligned cylinders, a hollow piston in each cylinder, integral means for connecting said pistons comprising a hollow casting consisting in a semi-circular portion and V-shaped portion adapted to establish communication between the interior of said pistons and also adapted to have a crank shaft extending therethrough and turnable there- in, and plate formations upon the sides of the casting adapted to support a wrist pin, and a connecting rod between the wrist pin and crank shaft whereby the pistons will be reciprocated with the rotation of said crank shaft.

ALBERT B. PEDERSEN.
